UNITED STATES PATENT OFFICE.

JULIOUS L. WEATHERS, OF SHELBY, NORTH CAROLINA.

ELECTRIC FIRE-ALARM.

1,172,852.

Specification of Letters Patent. Patented Feb. 22, 1916.

Application filed February 5, 1915. Serial No. 6,289.

To all whom it may concern:

Be it known that I, JULIOUS L. WEATHERS, a citizen of the United States, residing at Shelby, in the county of Cleveland and State of North Carolina, have invented certain new and useful Improvements in Electric Fire-Alarms, of which the following is a specification.

This invention relates to electric fire alarm systems, and more particularly to systems of this character which are automatically operated by an abnormal rise of temperature, or the presence of fire adjacent anyone of a plurality of stations.

The main object of the invention is to provide in connection with systems of this kind, an automatic circuit closer of improved construction, so arranged as to be instantly operated by a flame in its vicinity, however small.

A further object is to provide a circuit closer of this character which shall be simple in construction and positive and certain in its operation.

In order that the invention may be readily understood, reference is had to the accompanying drawings, forming a part of this specification, and in which,

Figure 1 is a central longitudinal section through my improved circuit closer; Fig. 2 is a plan view thereof with the cover removed, parts being in section; Fig. 3 is a central transverse section thereof, with the cover removed.

Referring to the drawings in detail, my improved circuit closer comprises a suitable base 1, near the center of which are mounted a pair of spaced combined contacts and binding posts 2 and 3, which project upwardly from the base. These contacts extend through the base so that their ends constitute binding posts to which the circuit wires 4 and 5 are secured.

The contacts 2 and 3 are adapted to be bridged by a bar or switch member 6, to which is attached one end of a helical spring 7, while the other end of such spring is secured at 8 to the base. A tubular housing 9, shown as square in cross section, incloses the spring 7, and is provided adjacent one end with a pair of slots 10, through which the switch member 6 extends and in which such member is free to slide. These slots constitute a guide for the switch member.

The switch member 6 is normally held out

of engagement with the contact posts 2 and 3, against the tension of the spring 7, by means of a fusible link 12, one end of which is secured to the switch member 6, as by means of a hook 11, while the other end is secured to the base, as indicated at 13. This fusible link may be formed either of an alloy of very low melting point, as is well known in the art, or may consist of a piece of combustible material, such as a cotton or cellulose string or thread, and it will therefore be understood that by the term fusible link, I intend to include all such equivalents. The switch member 6 and associated parts are inclosed by a suitable shield 14, secured to the base at either side.

Adapted to be secured to the base 1 in such manner as to envelop the parts previously described, is a cover or cage consisting of a frame 15, to which is attached a wire netting 16 of comparatively large mesh. This cage is entirely filled with loose inflammable material 17, such as raw cotton, tufts of which project through the meshes of the wire netting, as indicated at 18, so as to be exposed to any flame which may occur. It is therefore obvious that if a fire should break out so as to produce a flame in the neighborhood of a circuit closer so constructed, the cotton tufts would be immediately ignited and the cotton contained in the cage thus set on fire, the heat generated thereby serving to destroy the fusible link 12, and the spring 7 would thereupon operate to draw the switch member 6 against the contacts 2 and 3, thus closing the circuit.

What I claim is:

1. In a fire alarm system, an automatic circuit closer comprising a switch member, means for moving said switch member to circuit closing position, a fusible link normally restraining the movement of said switch member, a cage inclosing all of said parts, and a mass of combustible material filling said cage and projecting through the walls thereof.

2. In a fire alarm system, an automatic circuit closer comprising a switch member, means for moving said switch member to circuit closing position, a fusible link normally restraining the movement of said switch member, a wire cage inclosing said parts, and a mass of fibrous combustible material contained in said cage and having

portions projecting through the meshes thereof, whereby an outside flame may readily ignite the same.

3. In a fire alarm system, a circuit closer comprising a base, a pair of contact posts carried thereby, a switch member adapted to engage and electrically connect said posts, a spring urging said switch member toward said posts, a fusible link restraining the movement of said switch member, a mass of combustible material enveloping said parts,

and a shield secured to the base and extending over the switch member so as to protect the same from contact with the said mass of combustible material.

15

In testimony whereof I have affixed my signature in presence of two witnesses.

JULIOUS L. WEATHERS.
